UNITED STATES PATENT OFFICE.

CARL KÜHNL, OF WEIDEN, GERMANY.

DESIGN FOR A PLATE OR SIMILAR ARTICLE.

40,501.

Specification for Design.

Patented Feb. 8, 1910.

Application filed August 25, 1909. Serial No. 514,658. Term of patent 3½ years.

To all whom it may concern:

Be it known that I, CARL KÜHNL, a subject of the German Emperor, and a resident of Weiden, Bavaria, Germany, have invented a new, original, and ornamental Design for a Plate or Similar Article, of which the following is a specification, reference being had to the accompanying drawing, forming part thereof.

The figure is a plan view of a plate showing my design.

I claim:

The ornamental design for a plate or similar article substantially as shown.

CARL KÜHNL.
